The ornamental design for a control panel for elevator, as shown and described.

DESCRIPTION

FIG. 1 is a front, top and right side perspective view of a control panel for elevator, showing a first embodiment of our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is an enlarged cross-sectional view thereof; taken along line 7-7 of FIG. 2, with the internal system being omitted and forming no part of the claimed design;

FIG. 8 is an enlarged view thereof; taken along line 8-8 of FIG. 2;

FIG. 9 is a perspective view showing the control panel in use thereof;

FIG. 10 is a front elevational view showing the control panel in use thereof;

FIG. 11 is a front elevational view showing the control panel in use thereof;

FIG. 12 is a front elevational view showing the control panel in use thereof;

FIG. 13 is a front, top, and right side perspective view of a control panel for elevator, showing a second embodiment of our new design;

FIG. 14 is a front elevational view thereof;

FIG. 15 is a rear elevational view thereof;

FIG. 16 is a left side elevational view thereof;

FIG. 17 is a right side elevational view thereof;

FIG. 18 is a top plan view thereof;

FIG. 19 is an enlarged cross-sectional view thereof; taken along line 19-19 of FIG. 14, with the internal system being omitted and forming no part of the claimed design;

FIG. 20 is an enlarged view thereof; taken along line 20-20 of FIG. 14;

FIG. 21 is a perspective view showing the control panel in use thereof;

FIG. 22 is a front elevational view showing the control panel in use thereof; and,

FIG. 23 is a front elevational view showing the control panel in use thereof.

The broken line showing is included for the purpose of showing boundaries that form no part of the design to be patented.
